UNITED STATES PATENT OFFICE.

EDGAR MAYETTE, OF CANISTEO, NEW YORK.

AMUSEMENT APPARATUS.

Application filed March 25, 1927. Serial No. 178,311.

This invention relates to amusement apparatus designed primarily for use by children, the device being so constructed as to afford not only a comfortable chair for occupancy by the child but also to provide a movable toy member adapted to be driven by the movement of the chair impelled by the occupant.

A further object is to provide a movable toy structure having novel means for combining it with a rocking chair, the back and forth movement of the chair setting up a continuous rotation of the actuated portion of the structure.

A still further object is to provide a device of this character which is simple, durable and compact in construction, can be used either indoors or outdoors, and has the parts so assembled that the chair can be easily disconnected for use like an ordinary rocking chair and independently of the remaining portion of the structure.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the accompanying drawings, the preferred form of the invention has been shown.

In said drawings,

Figure 1 is a vertical longitudinal section through the complete structure.

Figure 2 is a bottom plan view thereof.

Figure 3 is an enlarged bottom plan view of a part of the driving mechanism.

Figure 4 is a horizontal section through the mechanism shown in Figure 3, illustrating the pawls and ratchet.

Figure 5 is a section on line 5—5, Figure 3, the ratchet being shown in elevation.

Figure 6 is a side elevation of a portion of one of the rockers of the chair and the centering means or guide used therewith.

Figure 7 is a section on line 7—7, Figure 6.

Referring to the figures by characters of reference 1 designates a rocking chair the back 2 of which, in the structure illustrated, is provided with a depending flange 3 below the seat 4. Each of the rockers 5 has a laterally extending stud 6 which can be formed

of a screw. The rockers 5 are mounted on base strips 7 each of which is provided, at its inner side edge with an upwardly extending flange 8, these flanges being arranged between the rockers 5 and close to them so as to prevent lateral displacement of the rockers relative to the base strips. Any suitable means, such as blocks 9, cross strips or the like can be used beneath the ends of the base strips 7 for supporting said strips off of the floor or other supporting surface on which the structure is mounted. A guide plate 10 is secured to and extends upwardly from the outer edge of each base strip 7 at the center thereof, each plate being provided with a slot 11 extending thereinto from its upper edge, said slot being flared upwardly and receiving one of the studs 6, as shown. Thus it will be seen that the chair 1 can be rocked on the base strips without becoming displaced relative thereto but it can be easily lifted off of the base and used with the rockers resting directly on the floor.

The base strips 7 are connected by cross strips 12 secured to the flanges 8, thus providing a base frame for supporting the chair. A longitudinal strip 13 is secured on the frame and has a lever 14 fulcrumed thereon. The upper end of this lever is connected by a pitman 15 to a yoke 16 having a clamping screw 17 or the like whereby the yoke can be readily attached to or detached from the flange 3. When the yoke is attached to this flange the rocking of the chair will result in oscillation of the lever.

Attached to the center of one end of the base frame is a tongue 18 which extends forwardly from the frame and is secured, at its forward end, between spaced brackets 19 attached to a pedestal base 20 supported by feet 21 or the like. The tongue can be detachably held to these brackets by removable bolts 22, thereby facilitating the separation of the parts when knocked down for shipment.

Guide brackets 23 are secured to the bottom surface of the base 20 and slidably mounted in these brackets is a strip or slide 24 one end of which is pivotally connected as 25 to a rod 26 which is hooked into the slide as shown at 25 and is pivotally connected to one end of lever 14. This rod is located beneath the tongue 18.

The pedestal includes upstanding members or standards 27 carried by the base 20 and supporting a head 28. A shaft 29

is journaled in the head and base, the lower end of this shaft being extended through a longitudinal slot 30 formed in the slide 24. Secured to the shaft 29 is a ratchet wheel 31 extending under the slide 24 and pivotally mounted on the shaft below the ratchet wheel are oppositely extending arms 32 each of which has a longitudinal slot 33 extending thereinto from its outer end. Slidable in each of these slots is a stud 34 extending from an ear 35 projecting laterally from the slide 24, it being understood that one of these ears 35 is provided for each of the two studs and that the two ears are extended in opposite directions. A pawl 36 is pivotally carried by each of the arms 32, the pawls being oppositely disposed and adapted to engage opposed portions of the ratchet wheel respectively. Springs 37 connect these pawls to the outer ends of their arms 32 so that the pawls are thus held normally in engagement with the ratchet wheel 31.

Any suitable structure adapted to be rotated is connected to the upper end of the shaft 29. In the form of device illustrated a large disk or table top 38 is shown secured to the shaft, this disk carrying a series of figure toys 39 so that when the disk or table top is rotated the toys will pass successively before the occupant of the chair. Obviously any other desired form of rotating toy can be connected to the shaft.

In practice the chair 1 is rocked back and forth. Thus the lever 14 is oscillated and will cause the slide 24 to be reciprocated. When the slide moves in one direction the two pivoted arms 32 will be swung about shaft 29 in the direction in which the slide is moving. Consequently one of the pawls will press against and rotate the ratchet wheel while the teeth of said wheel will slip past the other pawl. When the slide 24 is moved in the opposite direction the arms 32 will be swung in the direction in which the slide is moving so that the other pawl which was previously inactive, will engage the ratchet wheel and rotate it. Thus the reciprocation of the slide will result in application of power to the ratchet wheel from the respective pawls successively and the shaft 29, which is mounted to rotate freely, will thus be rotated continuously in one direction as the chair is rocked.

By detaching the yoke 16 from the flange

3 the chair can be removed from its supporting base and used independently of the driving mechanism.

What is claimed is:

1. The combination with a portable base 60 structure, of a movable toy member, toy driving mechanism connected to said structure, a rocking chair resting on and movably mounted relative to said structure, and an operative connection between the chair and the driving mechanism.

2. The combination with a portable base, 70 of a movable toy member, a supporting structure therefor, on the base, a rocking chair resting on and movable relative to said base and structure and means actuated by the rocking chair for moving the toy member.

3. The combination with a portable base, 75 of a movable toy member, a supporting structure therefor, fixed on but detachably connected to said base, a rocking chair removably mounted on the base, driving mechanism mounted on the base and supporting structure for actuating the toy member, and 80 a detachable operative connection between said mechanism and the rocking chair.

4. The combination with a movable toy member and a supporting structure therefor, of a base connected to said structure, a 85 rocking chair mounted on the base, a shaft journaled within the supporting structure, a slide carried by said structure, a driving connection between the rocking chair and the slide for reciprocating the slide when the chair is rocked, means actuated by the reciprocation of the slide for rotating the shaft in one direction, and a connection between the shaft and the toy member.

5. The combination with a movable toy member, a support therefor, a shaft journaled in the support and connected to the toy member, and a ratchet wheel secured to the shaft, of arms mounted to swing upon the shaft, spring controlled pawls carried thereby engaging the ratchet wheel, a slide mounted for reciprocation, a pivotal and 100 slidable connection between the slide and each of the arms, a rocking chair, and means actuated by the movement of said 105 chair for reciprocating the slide.

In testimony that I claim the foregoing as my own, I have hereto affixed my signature.

EDGAR MAYETTE.
